UNITED STATES PATENT OFFICE.

WILLIAM F. C. QUEHL, OF ST. LOUIS, MISSOURI.

PAINT-CAN.

SPECIFICATION forming part of Letters Patent No. 244,767, dated July 26, 1881.

Application filed June 18, 1881. (No model.)

To all whom it may concern:

Be it known that I, WILLIAM F. C. QUEHL, of St. Louis, and State of Missouri, have invented a new and useful Improved Paint Can or Bucket, of which the following is a specification.

This invention relates to metallic cans for the storing, preserving, and holding of paints, butter, jellies, and other contents that require to be securely closed or housed. The metallic can of this nature generally used is such that when it is desired to remove the contents from the can its cover had to be forced or cut open, and in case said cover was soldered to the bucket or can the latter could not be conveniently reused.

According to my invention the cover to close the open top of the can or bucket can be readily united to same to effectually house the contents; also, said cover can be entirely disconnected from the can or bucket when it is desired to remove the contents, and that without destroying the utility of the can or bucket, which therefore remains a convenient article for further and other uses.

Of the drawings, Figure 1 shows my improved can or bucket in elevation, the half to the left being a side elevation, the half to the right a sectional elevation. Fig. 2 is an enlarged side elevation, to show specially the metal band employed to secure the rim of cover to wired edge of bucket, and that the ends of said band are joined by an additional strip of metal. Fig. 3 is a plan view of Fig. 2, with the exception of the joining-strip of metal being left away, showing loose ends of the band and top of cover. Fig. 4 is an enlarged section taken on line $x-x$ of Fig. 2. Fig. 5 is an enlarged elevation of fastening-band fitted on can and cover; Fig. 6, plan view of part of cover only; Fig. 7, section of parts shown in Fig. 5, taken on line $x'-x'$.

Similar letters refer to similar parts throughout the several views.

A represents the metal can or bucket. The top circumferential edge of the bucket is as usual—viz., a turned-down edge, a , with or without the wire a' . (See Figs. 1, 4, 7.)

B is the cover, having annular vertical rim B' and projecting annular rim b , as usual. The cover can easily be inserted in the top of the

bucket, so that the rim b of cover shall rest upon the contiguous top face of the annular edge a of the bucket. (See Figs. 1, 4, and 7.)

In order to join the cover B to bucket A, so as to dispense with the use of solder and still obtain a sufficient closed joint of said parts, I proceed as follows:

c represents suitable packing, with which I encircle the cover's edge or rim b . Said packing therefore intervenes between the two edges—viz., b of the cover and a of the bucket. (See Figs. 1, 4, 7.) The use of the packing c is to prevent leakage and insure further protection to the contents.

D represents a circular metal fastening-band, which I employ as a fastening device to retain the cover-top of the bucket. This band is a strip of sheet metal or tin having its upper and lower edges crimped inward, and so that said band, in cross-section, has the shape clearly shown in Fig. 7. After the cover, with its interposed packing, has been fitted or placed in the bucket the fastening-band D is made to encircle both the rim-edges of cover and bucket; hence the edge d of the band rests on top of the rim b of the cover. Similarly the lower edge, d' of the band fits over the turn-down edge a of the bucket. (See Figs. 1 and 7.) As apparent, the edges d d' of the band can be pressed close against the contiguous edges of cover and bucket. This done, there remains but to fasten the two loose ends (shown at e e') of the band. (See Figs. 2, 3.) It is my object to so fasten or join the ends e e' of the band that same can be easily broken by the operator causing the band to spring apart preparatory to removing the cover and using the contents. This end I accomplish by soldering to the two ends e e' of the band the additional strip of light metal, F. (See Figs. 2, 4.) The ends of the band being so united, said band acts to retain the cover to its place, the joint, with the interposed packing, offering sufficient protection to the contents.

To remove the cover the operator simply breaks away the thin metal strip F. This done, the fastening-band D loosens its hold and springs apart, thus permitting the cover to be lifted from top of the bucket.

As apparent, the bucket can always be reused.

What I claim is—

1. In combination with the bucket or can A, having the turn-down edge *a*, the cover B, having projecting rim *b*, the interposed packing 5 *c*, the metal fastening-band D, having upper and lower edges, *d d'*, the ends of said band joined together by a strip of metal, F, substantially as and for the purposes set forth.
2. The bucket or can A, having its cover B 10 joined to the top edge of the bucket by means

of a metal fastening-band, D, the two loose ends of which are joined together by a separate strip of thin metal, F, substantially as and for the purposes set forth.

In testimony of said invention I have here- 15 unto set my hand.

WILLIAM F. C. QUEHL.
